(57) **CLAIM**

The ornamental design for a control panel for incubator as shown and described.

DESCRIPTION

FIG. 1 is a front, top, right side perspective view of a control panel for incubator according to the first embodiment, showing our new design;

FIG. 2 is a front, bottom, right side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view thereof within a frame 9 in FIG. 1;

FIG. 10 is an enlarged view thereof within a frame 10 in FIG. 2;

FIG. 11 is a front, top, right side perspective view of a control panel for incubator according to the second embodiment, showing our new design;

FIG. 12 is a front, bottom, right side perspective view thereof;

FIG. 13 is a front view thereof;

FIG. 14 is a rear view thereof;

FIG. 15 is a left side view thereof;

FIG. 16 is a right side view thereof;

FIG. 17 is a top view thereof; and,

FIG. 18 is a bottom view thereof.

The evenly dashed broken lines shown in the drawings illustrate environmental structure in which the claimed design is used, and portions of the article, that form no part of the claimed design. The unshaded area immediately
